UNITED STATES PATENT OFFICE

2,172,513

APPARATUS FOR CONSERVING LOW BOILING HYDROCARBON VAPORS OF CENTRIFUGED OIL

Hans Olof Lindgren, Appelviken, Sweden, assignor to The De Laval Separator Company, New York, N. Y., a corporation of New Jersey

Application March 12, 1938, Serial No. 195,663
In Sweden March 24, 1937

1 Claim. (Cl. 196—46)

In the production of benzine and similar low boiling but normally liquid hydrocarbons, the latter usually are subjected to refining with concentrated sulphuric acid. This is now often effected by mixing, for example, the crude benzine with concentrated sulphuric acid in a suitable apparatus permitting of continuous operation and by subsequently separating the mixture in a centrifugal separator; refined benzine and so-called sludge thereby being obtained. Often it cannot be avoided that the temperature of the mixture during separation is relatively high and higher than the boiling point of some of the constituents of the benzine. Vapor is thereby easily formed in the benzine, especially during the strong mechanical action to which the liquid is subjected when it is thrown out of the separator bowl into the collecting vessel. It has not been possible to prevent part of the fumes from penetrating down to the oil bath of the separator, which entails a dilution and deterioration of the lubricating oil. The fumes also sometimes escape to the room in which the separator is erected, which causes discomfort for the operators.

According to the present invention these inconveniences are avoided by making the chamber which surrounds the centrifugal bowl and into which the liquid is thrown when it leaves the bowl gas-tight from the atmosphere, and by connecting it through a gas pipe with the ventilation system which is normally arranged in an oil refinery. This ventilation system, by which all those tanks in the refinery communicate in which hydrocarbon fumes may be evolved, communicates with the atmosphere only through an installation for the recovery of the hydrocarbons in liquid form, for instance, by means of active carbon. If an evolution of gases takes place in the separator with this arrangement, the gases cannot escape directly to the air, but are forced to pass through the recovering installation, any losses thereby being avoided.

A separator of the present type substantially consists of a chamber enclosing the driving mechanism of the machine and another chamber for the separator bowl, the latter chamber communicating with the collecting vessels into which the liquid is thrown when it leaves the bowl. By providing a packing device between the chamber enclosing the driving mechanism and the chamber in which the bowl is arranged, it is possible to prevent any fumes from penetrating into the chamber for the driving mechanism and contaminating the lubricating oil. The provision of a packing in this place, however, presents certain

difficulties, because a tight joint must be established around the rapidly rotating spindle which carries and drives the bowl. On the other hand, it is possible to establish a reliable tightening of means of, for instance, a liquid seal around the spindle or a labyrinth packing. There is, however, nothing that prevents the chamber for the driving mechanism, an oil bath for which such chamber usually contains, from being made a part of the space separated from the atmosphere but communicating with the ventilation system. It is thereby not possible to prevent a condensation of hydrocarbons in the lubricating oil, but this objection may be avoided by either changing the oil at suitable intervals or by driving off the hydrocarbons condensed in the oil continuously by means of a special arrangement.

It is often advantageous to arrange a container comprising several compartments and provided with inspection glasses, test cocks, etc. in the neighborhood of the separator, to which compartments refined benzine, goudron, excess liquid, etc. are conducted and which communicate with each other at the upper part through the ventilation channel. The conduit through which, as stated before, the separator communicates with the ventilation system of the refinery is then coupled to the said container, the gas space of which in turn communicates with that of the separator, either through a special ventilation pipe or through the discharge pipes for liquid, the diameter of which is then sufficiently large to insure that they will not fill with liquid.

The accompanying drawing is a side elevation, largely diagrammatic, of an installation of one embodiment of the invention. In the figure, 1 is the separator frame, in the lower chamber 2 of which the driving mechanism 3 is located, and in the upper chamber 20 of which the separator bowl 4 is arranged. The latter is surrounded by the collecting vessels 5, 6 and 7 which are hermetically separated from the atmosphere. For this purpose, among other things, a packing device is arranged at the spindle bearing 8 or in the place 9 where the horizontal driving shaft 45 extends through the frame. The different collecting vessels communicate by pipes with the container 10. The various collecting compartments 12, 13, 14 and 15, which are provided with inspection glasses 11, communicate at the upper part with each other, and the container communicates by pipe 16 with the ventilation system 17 of the refinery, which communicates with the air through the arrangement 18 for the recovering of the hydrocarbons. 19 represents a tank 55

containing the liquid mixture to be subjected to the centrifugal separator. This supply tank is connected through a feed pipe 21 and feed pump 22 to the centrifugal separator. The tank 19 is shown as also communicating with the pipe 16 so that any vapor forming in the mixture before centrifugation will also escape into the ventilating pipe 17.

What I claim and desire to protect by Letters Patent is:

10 The combination with a centrifugal separator for refining low boiling liquid hydrocarbons and collecting vessels surrounding the separator and

closed to the atmosphere and adapted to receive the separated constituents and each provided with a single fluid outlet, of a recovery system for condensing condensable hydrocarbon vapors, receivers for the separated liquids, closed fluid passages between the respective outlets from the collecting vessels and the respective receivers for conveying to the latter both separated liquid constituents and vapors, and a closed vapor passage connecting the vapor spaces of the receivers with the recovery system. 5 10

HANS OLOF LINDGREN.
